UNITED STATES PATENT OFFICE.

ANSON C. MILLS, OF JACKSON, MICHIGAN, ASSIGNOR TO JACKSON FENCE COMPANY, OF JACKSON, MICHIGAN, A CORPORATION OF MICHIGAN.

MEASURING DEVICE FOR FENCE-MACHINES.

1,335,980.

Specification of Letters Patent.

Patented Apr. 6, 1920.

Application filed January 11, 1917. Serial No. 141,904.

To all whom it may concern:

Be it known that I, ANSON C. MILLS, a citizen of the United States, and resident of Jackson, in the county of Jackson and State 5 of Michigan, have invented certain new and useful Improvements in Measuring Devices for Fence-Machines, of which the following is a specification.

In the operation of fabric machines it is 10 necessary for most efficient operation to provide means for producing desired lengths of the fabric. In some instances a number of rolls may be required of the same length and these means should be so arranged as 15 to provide for this production without more than ordinary attention on the part of an operator.

An object in the present device is to provide means of such character as to enable 20 the production of any desired lengths and to produce as many of such lengths as may be desired without further adjustment. To this end I have provided means directly connected to the main shaft of a wire fabric 25 machine for rotating an arm, the extent of rotation of the arm being controlled by a predetermined setting, an electrical circuit being closed at the completion of the movement of the arm whereby the machine may 30 be stopped or a warning signal be given.

The invention will be more readily understood by reference to the accompanying drawings, wherein—

Figure 1 is a plan view of a device constructed in accordance with my invention;

Fig. 2 is a side elevation thereof;

Fig. 3 is a transverse vertical sectional view, and

Fig. 4 is a vertical sectional view on the 40 line 4—4 of Fig. 3.

In the drawings the casing which incloses the parts is indicated at 10, the back wall 11 thereof constituting a bearing for a shaft 12. On the overhung end of the shaft is 45 mounted a gear 13 adapted to be engaged by a pinion 14, fast on a ratchet wheel 15. The shaft which supports the pinion and ratchet wheel is mounted in a bracket 16, best shown in Fig. 2. Also mounted on the shaft 17 50 which carries the ratchet wheel is an oscillating arm 18 having a slotted outer end to which the link 19 is adjustably connected. The link engages an eccentric 20 connected to or actuated by the main shaft of the ma-

chine, the arrangement being such that the 55 arm 18 is oscillated. A pawl 21 is connected to the arm 18 and engages the periphery of the ratchet wheel at one side thereof. The inner end of the arm 18 is provided with a fragmentary gear 22, which engages with 60 a similar gear 23, carried by a shorter arm 24, pivoted at 25 to a suitable support. The outer end of the arm 24 carries a pawl 26, which engages the periphery of the ratchet wheel 15 at a point substantially opposite to 65 that of the point of engagement of the pawl 21. By reason of the arrangement shown, it will be seen that the ratchet wheel is advanced during both motions of the arm 18. This provides for a finer adjustment and a 70 more uniform movement of the gear 13.

Pinned to the shaft 12 and mounted inside of the rear wall 11 of the casing is a collar 27 provided with clutch teeth 28, which engage with projections on a disk 75 29, loosely mounted on the shaft 12. A pair of disk members 30, 31, engage the disk 29 and tend to clamp the same under the action of the springs 32. The disk 30 is provided with a knob 33, or similar manually-operable projection, and also with an arm or pointer 34. The axis of the disk member 30 is hollow and provides a bearing for the inner end of the shaft 12. The outer wall 35 of the casing 10 is removably secured in 80 place. In a circular recess in the face of the member 35 I mount a flat ring 36 having notches 37 in its flanged periphery. The ring 36 is retained in position by means of the ring 38 and fastening screws 39, but is 85 readily rotatable in its seat by manually engaging the knob or projection 40.

Formed as a radial projection from the disk member 30, as best shown in Fig. 4, is the arm 41, which in the dotted line position 95 of Fig. 4 is adapted to engage the rod or plunger 42 and close a switch 43 in a circuit 44. In the circuit may be located a solenoid 45, by means of which the machine may be stopped, or a light or bell may be employed 100 as a warning, or both may be used.

It will be understood that the machine may also be stopped by pneumatic, hydraulic or mechanical means but as the invention does not reside in the stop mechanism, only 105 the electrical means are illustrated.

The operation is as follows: Assuming that it is desired to produce thirty rod

lengths of fabric, the flat ring 36 is moved by manually engaging the knob 40 until the notch corresponding to the correct length registers with a dog or catch 46. The knob 33 is then grasped by the operator and rotated counterclockwise until the arm or pointer 34 contacts the knob or stop 40. The machine is then started and under the action of the coöperating parts the disk member 30 and its radially projecting arm are rotated clockwise as viewed in Fig. 4, or until the arm 41 closes the circuit 44. If the machine is not at once shut off no harm is done because the clutch members permit the parts to slip. After the correct length has been secured, the operator returns the pointer 34 to its original position by a single movement of his hand and the operation is repeated.

The extent of movement of the arm 41, which determines the length of the fabric to be woven is fixed by the adjustment of the graduated ringlike member; that is, by that means the knob 40 is located and this determines the extent to which the pointer 34 may be rotated counterclockwise.

Obviously many modifications may be made in the construction shown and I do not wish to be limited to the exact form shown and described.

30. I claim:

1. In a measuring device for fence machines, the combination of a ring-like stop member having peripheral graduations, a rotatable measuring device mounted adjacent to said stop member and including an arm for contact with said stop and a friction clutch, mechanical means operating through said clutch for moving said measuring arm away from said stop in timed relation with said machine, and means adapted to be actuated at the termination of the pre-determined travel of said measuring member for causing the interruption of the operation of said machine, substantially as described.

2. In a measuring device for fence machines, the combination of a flat ring the periphery of which is graduated, a stop member mounted on the ring, a measuring member including a friction clutch, and an arm or pointer for coöperation with said stop member, means operated by the fence machine for transmitting motion to said measuring member through said clutch, and an electric circuit adapted to be closed by said measuring member upon the completion

of its pre-determined travel, substantially as described.

3. In a measuring device for fence machines, the combination of an adjustable stop member having graduations, means for locking the stop member at a desired point, a stop on said stop member, a measuring member frictionally connected to the fence machine, said measuring member being provided with a limiting stop adapted to engage with the stop on said stop member at the beginning of its measuring movement, and machine-interrupting means connected to said measuring device and operable at the completion of the predetermined travel thereof, substantially as described.

4. In a measuring device for fabric machines, the combination of a graduated member having a stop, means for securely locking said graduated member in a desired position, a measuring member having an arm adapted for coöperation with said stop, said measuring member being frictionally connected to a machine, the product of which is to be measured, said measuring member being manually movable against the friction of the clutch to its initial position in which the arm and stop are in contact, and machine-interrupting means adapted to be actuated by said measuring member upon the completion of its predetermined travel, substantially as described.

5. In a device of the class described, the combination of a casing, a stop mounted for angular adjustment about an axis in said casing, a machine-interrupting device, a shaft mounted at the said axis of the casing, a pair of arms carried by the shaft, one arm being adapted to coöperate with said stop and the other with said machine-interrupting device to actuate the same, means connected to the machine to be controlled for rotating said shaft in one direction when the machine is in operation, and a friction clutch between said shaft and said connecting means whereby said shaft may be rotated to move the arm to the limit permitted by the adjustable stop without affecting said connecting means, substantially as described.

Signed at Chicago, Illinois, this 12th day of December, A. D. 1916.

ANSON C. MILLS.
